UNITED STATES PATENT OFFICE

2,603,467

CARBURETOR

William R. Kutik, Jr., Butler, and Jack Goodman,
Fair Lawn, N. J.

Application May 3, 1949, Serial No. 91,114

3 Claims. (Cl. 261—21)

1

This invention relates to improvements in carburetors and is particularly directed to a device adapted to vaporize liquid fuel for internal combustion engines.

The primary object of this invention is to convert liquid fuel into finely divided vapor and to deliver the fuel in such a state for ignition, whereby quicker and better combustion may be obtained, and greater energy may be derived from the fuel.

Another important object of this invention is to agitate and break up the liquid fuel into a finely divided vapor by mixing air with the fuel at various stages, and agitating the vapor laden air whereby the charge is concentrically treated before entry.

A meritorious feature of this invention resides in the provision of a device having means for saturating air with liquid fuel, and agitating the air, at each change of the air mixing stage, until the air is delivered for ignition in a finely divided vaporized state.

Another object of this invention is to provide a vaporizing device, which is simply and compactly constructed, which is easy to install for use in an internal combustion engine, and which is durable and efficient in operation.

These ancillary objects and other structural features of merit are obtained by this invention, a preferred embodiment of which is set forth in the following description, and illustrated in the accompanying drawings, where:

Figure 1 is a side elevational view of a device, constructed in accordance with the principles of this invention;

Figure 2 is a bottom plan view thereof;

Figure 3 is a vertical sectional view;

Figure 4 is a transverse sectional view, taken on a line 4—4 of Figure 3;

Figure 5 is an enlarged detail sectional view, taken on a line 5—5 of Figure 3;

Figure 6 is an enlarged detail view, taken on a line 6—6 of Figure 4.

Referring now more particularly to the drawings, this invention generally designated by the character reference 10, includes a liquid fuel housing 12 formed with an open internally threaded upper end, which is closed by a detachable cap 14, having a center vertical opening 16. The housing terminates at its lower end in a coaxially reduced extension 18, the latter being formed with a centrally disposed vertical passage 20, which terminates in a valve seat 22. A fuel intake line 24 is secured to the enlarged passage 26, communicated with the valve seat 22, and formed at the outer end of the extension.

2

A needle valve 28 is disposed in the passage 26 and adapted to seat in the valve seat 22. The needle valve includes a stem 30, which is disposed through the passage 20 and terminates in an externally threaded end 32, the latter being disposed through the opening 18 in the cap. A float 34 is concentrically slidably disposed on the stem of the needle valve and the upward movement of the float thereof is controlled by an adjustment nut 36 engaged on the threaded shank 32 of the stem.

The fuel housing 12 is communicated with and forms a part of the carburetor 38. Conduit means 40 extends between the fuel housing and the outer wall 42 of the carburetor. The carburetor includes a casing or housing 44, about which is concentrically disposed the outer wall 42, the latter being spaced from the outer surface of the housing 44 to define an air chamber and fuel chamber 46. The lower end of the housing 44 is open, the housing terminating in a lateral annular flange 48 which is engaged at its outer extremity in an annular recess 50 formed at the lower end of the wall 42, whereby a sealed joint is formed between the housing 44 and the wall 42 at the lower end thereof. A cap 52 is formed with annular internally threaded flange 54, the latter being threadingly disposed on the externally threaded end 56 of the wall 42, with a sealing ring 58 provided and disposed between the cap and the flange 48 of the wall for the housing 44.

The wall 42 terminates at its upper end in an inwardly directed laterally disposed annular flange 62, which is concentrically disposed and engaged on the outer surface wall of the housing 44. The flange 62 is formed with a plurality of circumferentially spaced air inlet tubes 64, whereby air is admitted into the chamber 46, the liquid fuel being admitted into the lower end of the chamber through the connecting pipe 40. The air entering through the air inlet tubes 64 in the flange 42 passes downwardly in the chamber 46 and mixes with the raw fuel, which is retained at the lower end. A plurality of vertically disposed tubes 66 are disposed in the housing 44 and are formed at their upper ends with annular extensions 68. The extensions 68 extend through the wall of the housing 44 and communicate with the chamber 46 at the upper end thereof. Thus, the fuel laden air rises in the chamber 46 and is drawn through the tubes 66 into the interior of the housing 44. The dispersing means 70 includes a chamber formed by the housing 44 and is completely filled with a material 72, such as steel wool or a similar material which can be employed for dispersing the fuel laden air into an extremely finely divided vaporous condition during the progress

therethrough and operates as a filtering medium.

The upper end of the housing 44 terminates in a coaxially reduced internally threaded coupling end 74, which is attached to an offset extension 76 of an intake pipe 78. The offset extension 76 extends inwardly of the pipe 78 and forms a nozzle 80, substantially closed at one end and terminating in an externally threaded opposing discharge end 82. A nozzle tip 84 having a discharge passage 86 formed therein is threadedly disposed on the discharge end 82 of the nozzle. A throttle valve 88 is slidably disposed in an opening 90 at the end 80 of the nozzle and terminates in a needle valve 92 which is disposed in the passage 86 in the tip. An actuating rod 94 is rotatably disposed transversely through the extension 76 and a link 96 is actuated thereby the link terminating in a yoke end 98. The yoke 98 is pivotally disposed on a block 100 which is threadedly disposed on the threaded shank of the rod 88. An operating lever 102 is formed with a bifurcated offset end 104, which is secured on the extending outer extremity of the rod 94 by fastening means 106.

A plate 108, which is arcuately formed, to conform to the configuration of the pipe 78 is secured by screws 110 to the top of the plate in vertical alignment with the fuel discharge nozzle. The plate permits a convenient and quick adjustment of the internal structure of the nozzle or fuel control means.

The vaporized fuel and vapor laden air is admitted into the pipe 78 through the nozzle tip 84 and is mixed with a secondary source of air. The air is sucked in through the end 112 of the air intake pipe 78. A valve 114 is pivotally disposed adjacent the end 112 of the air intake pipe and is mounted on a rod 116 transversely journaled through the pipe. A plate 118 is secured on the outer extremity of the rod 116 at one end and is secured to a coil spring 120 at the other end. An S-shaped bracket 122 is mounted on the upper portion of the pipe and extends upwardly above the plate 118. A screw 124 is carried by the bracket and is adapted to receive the upper end of the spring 120. Thus, the valve 114 is normally retained in a vertical position, closing off the air intake pipe 78. However, the valve 114 is automatically controlled by the vacuum and is opened thereby to automatically admit a supply of air. Of course, the air intake tube 78 discharges the fuel to the ignition point through a connecting pipe 126.

The operation of this device is simple and is as follows:

The liquid fuel enters the fuel housing through the pipe 24 and is maintained at a level, through the float 34 and needle valve 28, thus when the desired amount of liquid fuel is disposed within the fuel housing the float is raised and correspondingly moves the needle valve into its seat preventing the admission of further fuel. The fuel is conducted by the communicating pipe 40 to the chamber 46 and is maintained at the bottom thereof. This point is the closest point that the raw fuel gets to the ignition point. Air is admitted through the air inlet tubes 64 into the chamber 46 at a point below the level of the fuel and mixes with the fuel in the bottom portion, thereby agitating the fuel. The vapor laden air then rises to the chamber and is drawn through the tubes 66 into the dispersing means. The air then passes thru the chamber 70 of the dispersing

means and the fuel laden air is agitated to a finely divided state. The air then is admitted into the air intake pipe 78, through the throttle valve, where it is mixed with the intake air which is admitted through the end 112, by the automatic control means provided. The passage of the fuel laden air into the air intake pipe causes further dispersion of the fuel laden air. The mixture is then delivered through the pipe 78 to the ignition point.

Thus, it can be seen that there is provided a novel and durably constructed carburetor, whereby raw liquid fuel is converted into finely divided vapor and the finely divided vapor is admitted to the ignition point, so that a quick and clean combustion is obtained and the utmost energy is obtained from the fuel.

Having described the invention, what is claimed as new is:

1. In a carburetor, a vertical casing member including inner and outer cylindrical walls joined at their ends with the outer periphery of the inner wall spaced radially inwardly from the inner periphery of the outer wall to define an air and fuel chamber, inlet means at the upper end of the casing member extending into the chamber, a source of fuel including a supply nipple extending through the lower end of said outer wall and into the chamber, a plurality of circumferentially spaced vertical tubes disposed within the inner wall and having lower ends spaced above the bottom of the casing member, said tubes including upper inclined ends extending through said inner wall and into the chamber at the upper end thereof to receive air entering the chamber through said inlet means, an absorbent material disposed within said inner wall, and a valve controlled inlet passageway connected to the upper end of said inner wall and having a portion adapted to be positioned in an intake manifold.

2. The combination of claim 1 wherein said source of fuel includes a fuel housing having an inlet opening and a removable top wall, a float in the housing, and a rod slidably carried by the upper wall and terminating in a valve for selectively opening and closing the inlet opening of said housing, said float being slidably supported on said rod, and an abutment threaded on the rod above the float.

3. In a carburetor, a vertical casing member including inner and outer cylindrical walls joined at their ends with the outer periphery of the inner wall spaced radially inwardly from the inner periphery of the outer wall to define an air and fuel chamber, inlet means at the upper end of the casing member extending into the chamber, a source of fuel including a supply nipple extending through the lower end of said outer wall and into the chamber, a plurality of circumferentially spaced vertical tubes disposed within the inner wall and having lower ends spaced above the bottom of the casing member, said tubes including upper inclined ends extending through said inner wall and into the chamber at the upper end thereof to receive air entering the chamber through said inlet means, an absorbent material disposed within said inner wall, an L-shaped inlet pipe having a portion disposed alongside of said casing member and a portion extending horizontally over said casing member, a passageway formed with the horizontal portion of said pipe and extending downwardly therefrom and coupled to the upper end of said inner wall, said passageway having an

upper end positioned in the horizontal portion of said pipe, a nozzle attached to the upper end of said passageway, and a valve controlling the passage of mixture outwardly through said nozzle from said passageway.
